UNITED STATES PATENT OFFICE.

JAMES A. HERRICK, OF NEW ROCHELLE, NEW YORK.

GAS-PRODUCER.

1,210,471.

Specification of Letters Patent. Patented Jan. 2, 1917.

Application filed September 26, 1913. Serial No. 791,898.

To all whom it may concern:

Be it known that I, JAMES A. HERRICK, a citizen of the United States of America, and resident of New Rochelle, in the county of 5 Westchester and State of New York, (whose post-office address is No. 193 Mayflower avenue, New Rochelle, New York,) have invented certain new and useful Improvements in Gas-Producers, of which the following is a specification.

This invention relates to gas producers, and has for its object to provide an apparatus of such construction that the mass of fuel within the combustion zone will be kept 15 from clogging, and the formation of crevices or fissures prevented, while the discharge of ashes from the ash zone may be accomplished at desired intervals without interfering with the operation of the producer; 20 these objects being attained by providing a rotatable section inclosing the combustion zone and provided with driving means, and another rotatable section inclosing the ash zone but not provided with driving means, 25 and means for coupling the two sections together at will, so that rotation of the combustion-zone section will effect rotation of the ash-zone section.

Other objects and aims of the invention, 30 more or less broad than those stated above, together with the advantages inherent, will be in part obvious and in part specifically referred to in the course of the following description of the elements, combinations, arrangements of parts, and applications of 35 principles constituting the invention; and the scope of protection contemplated will appear from the claims.

In the accompanying drawings, which are 40 to be taken as a part of this specification, and in which I have shown one of the various possible embodiments of this invention as at present preferred: Figure 1 is a vertical sectional view, taken through the producer; 45 Fig. 2 is a horizontal sectional view taken on the line 2—2 of Fig. 1, with certain of the parts shown in plan; Fig. 3 is a vertical sectional view, taken on the line 3—3 of Fig. 50 2; Fig. 4 is a top plan view of certain parts shown in Fig. 1; Fig. 5 is an enlarged detail view, partly in section and partly in elevation, showing a possible means of intermittently and selectively coupling up a rotative section and a normally fixed section of 55 the producer, and this detail view may be assumed to be taken on the line 5—5 of

Fig. 1; Fig. 6 is a top plan view of the parts shown in Fig. 5; and Fig. 7 is a view similar to Fig. 2, but showing a slightly different arrangement of slightly dissimilar but practically equivalent parts.

Similar reference characters refer to similar parts throughout the several views of the drawings.

Referring now to the drawings, A represents the casing of a producer, the same being constituted in the present instance by upper, intermediate and lower sections 8, 9 and 10, respectively, the upper section being supported in the usual manner by means of 60 a suitable plurality of uprights 11 (but one of which is here shown) which rest upon the foundation or setting 12.

The lower section 10 of the producer tapers inwardly as shown at 13, which 75 tapered portion carries an annular track 14 which rests upon rollers 15 revolvably journaled in brackets 16 carried by uprights 11. Although the track 14 and the co-operant rollers 15 are here provided, lower section 80 10 is normally non-rotatable, these rollers in the main merely supporting said lower section at a suitable horizontal location.

The means provided for revolving the intermediate section 9 comprises a gear 85 wheel 17 which meshes with teeth formed upon the annular member 18 encircling said section and fixedly secured thereto. Gear wheel 17 is carried upon the shaft 19, which shaft is suitably supported and receives its 90 power from any suitable source.

Numeral 20 indicates a receptacle or basin formed in the setting 12 underneath the body of the producer into which dips the tapering end 13 of lower section 10. The 95 lower end of the latter extends below the level of the water in the basin, whereby the lower end of the producer is trapped or sealed. Basin 20 is also adapted for receiving ashes which are discharged from the 100 lower end of the producer and which may be removed by any suitable means, a space for this purpose being provided between the lower end of the producer and the side walls of the basin. The discharge of ashes 105 from the producer into the basin is regulated as hereinafter described by means of selectively and intermittently rotating the lower section 10, the fixed ash-bed normally resting above the twyer box 21 (a merely 110 preferable type of such twyer box being here disclosed) which is supported as shown

upon the upper end of the blast pipe 22. To provide for the discharge of water of condensation or any other liquid which may enter the interior of the blast pipe 22, there is provided a discharge conduit 23.

In order that intermediate section 9 may be revolved, annular member 18 carries on its underside as shown an annular track 24, this track resting upon rollers 25 journaled within brackets 26 carried by uprights 11.

Intermediate section 9 is water-sealed to lower section 10 by any well-known means, as for instance, indicated at 47, and said section 9 is also similarly water-sealed to upper fixed section 8 as at 28. Located within upper section 8 of the producer and depending from the cover 29 is an annular curtain or partition 30. This annular partition or curtain is spaced from the inner walls of section 8 to form a mixing chamber 31 and leading from this mixing chamber is preferably a plurality of upcomers 32, rather than a single upcomer as heretofore employed, in the present instance two upcomers 32 being disclosed for purposes of illustration. These upcomers 32 here lead into a common main 33 as shown.

Upper fixed section 8 is here preferably, but not necessarily, constructed of a plurality of joined ring-subdivisions, in connection with which it should be noted that certain other of the sections could be so constructed; and that curtain 30 is also here preferably so constructed, a detailed description of the construction of each of which and their possible utilizable cooling circulations or other structural features will be taken up hereinafter. In this connection it should be noted that the partition 30 here disclosed is intended as an improvement upon and a structural variation from a generally similar device disclosed and claimed in Letters Patent No. 1,001,953, heretofore issued to this applicant on August 29th, 1911.

Cover 29 carries a plate 34 (see also Fig. 4) which is here provided with a circular opening 35 to communicate with the interior of curtain 30. Plate 34 also carries a pair of parallel tracks 36, upon which is slidably mounted a truck 37, and the latter carries two openings 38 and 39 respectively (see Fig. 4), the former in one adjustment of the truck 37 upon the plate 34 registering with opening 35, and the latter in another adjustment of said truck registering with said opening 35. Opening 38 has associated therewith a removable cover plate 40 and opening 39 has associated therewith a hopper 41 and removable hopper cover 42. Any means for shifting truck 37 upon its tracks 36 may be employed, in illustration whereof there is disclosed in Fig. 4 a breast-bar 43 rigidly carried by truck 37. Thus

were it desired to feed fuel into the interior of the producer continuously and via the interior of the partition 30, it will readily be seen that it is merely necessary, for instance, to shift the truck 37 so that its opening 38 registers with the opening 35, then remove the cover plate 40, and then in any suitable manner feed the fuel through the registered openings 38 and 35.

Referring now to a possible construction of the partition 30, attention is directed to a plurality of depending stirring members 44 preferably carried thereby as shown, which may or may not be used in connection with this embodiment of this invention. These members 44 here depend within the fuel zone supported by intermediate section 9, and since said section is preferably continuously rotated, the members 44 will serve a useful agitative function if employed. These members may be water-cooled or otherwise equipped with heat insulating instrumentalities as desired.

In Fig. 1 a poker 45 of any type is indicated in dotted lines and presumed to be mounted in a preferably gas-tight ball-and-socket support 46 whereby said poker, if employed here, may be varyingly adjusted to extend into the interior of intermediate section 9. Or the said poker 45 and said support 46 may respectively be located as indicated in dotted lines at 45' and 46'. Additional agitation may be effectuated with reference to the fuel mass in the producer by means of the introduction, if desired, of a poker or the like through the opening 35.

If the lower section 10 be made continuously rotatable with the intermediate section 9, the ashbed normally located above the twyer box 21 will not be intermittently stable enough for economic operation of the producer, inasmuch as a steady flow of ashes is precipitated or spewed downwardly by centrifugal action, this in turn lowering the upper level of the fuel mass at a too rapid and wasteful rate. On the other hand, if lower section 10 be rigidly set in place and permanently anchored, as has been the general practice heretofore, the ashes will at intervals have to be laboriously dug out by hand and with much sacrifice of efficiency. The present disclosure in this connection will partake of all the advantages of a continuously rotatable lower section 10, but will not include any of the disadvantages of such a construction. As hereinbefore stated, lower section 10 is normally immovable upon its roller supports, intermediate section 9 being preferably continuously rotating at a suitable speed. As shown in Fig. 1, but as more clearly disclosed in Figs. 5 and 6, the usual annular water-accommodating trough 47 carried by lower section 10 for co-operation with the depending annular curtain 48 is here provided with a plurality of spaced

pockets 47' integrally webbed upon the usual casting which constitutes the annular trough aforesaid. The wall 47" shown in Fig. 5 may be transversely apertured, if desired, to the end that the water within trough 47 may circulate through each pocket and cool the same. Intermediate section 9 is provided with a plurality of angle brackets 49 to a number preferably corresponding to the number of pockets 47' employed on lower section 10, the angle brackets 49 being also preferably spaced uniformly and in similarity to the spacing of pockets 47'. The pockets are each adapted to accommodate here a manually insertible and removable bolt 50. When it is desired to intermittently rotate with intermediate section 9 the lower and normally immovable section 10, it is merely necessary, when it is remembered that the usual rate of rotation of intermediate section 9 is exceedingly low, to insert within each pocket 47' a bolt 50, the preferable method of insertion of which bolts is to commence the insertion of said bolts one after the other at the instant when the angle brackets 49 have just passed the fixed location of the pockets 47', a suitable interval of time being thus provided for a single attendant to install all of the bolts 50 before the angle brackets 49 are transported to proximity with a new series of pockets 47'. This will insure that each angle bracket 49 will simultaneously advance into contact with a bolt 50 and obviate any danger of shearing any lesser plurality of said bolts than the plurality which in accordance with the size of the producer and the inertia of the lower section 10 is predetermined as adequate to withstand as a group the strain of overcoming the inertia of lower section 10. In this manner, the continuously rotating intermediate section 9 may when desired set up a temporary and an accompanying rotation of lower section 10 automatically to spew downwardly the accumulated surplusage of ashes, and this without any necessity for preparatorily ceasing the rotation of intermediate section 9 to retain the coupling of section 9 and section 10 as above described. When lower section 10 has sufficiently rotated, its temporary connection with intermediate section 9 may be terminated; and probably in the present instance it will be found desirable, for this uncoupling, to cease for a short space of time the rotation of intermediate section 9. The sections now being considered are, of course, uncoupled here by removing the bolts 50 from the pockets 47'. It should be understood, however, that the utilization of auxiliary means to intermittently rotate lower section 10 is within the scope of this invention, or the utilization of coupling instrumentalities other than the angle brackets 49 and the bolts 50, whether or not such other

coupling instrumentalities be adapted for being made effective or ineffective during the rotation of intermediate section 9.

It should be understood, then, that the fuel falls automatically as the ashes are shaken down, and especially so in the presence of the fuel-receiving partition 30 (which may be here utilized), and the fire is thus solidified. It is reiterated that a fundamental feature of this improvement is the fact that a construction is shown in connection with which means of various characteristics could be employed. The salient structural idea is the division of a normally lower revolvable producer section 80 into a plurality of sections, as the present sections 9 and 10, either of which is independently rotatable, or both of which are simultaneously rotatable. Thus here it could be arranged to give automatic actuation to either or both of the sections 9 and 10. It is obvious for instance that the driving shaft 19 could be utilized to cause the predetermined rotation of section 10 independently of the middle section. It is also obvious that means for simultaneously removing or inserting the bolts 50, or their equivalents, could be readily used, and for doing this, if desired, at stated times or as determined by the attendant. All the foregoing to the end that the ashes may be removed and the coal settled as necessary, so that, in accordance with the speed or speeds of rotation of one or both of said sections, and in accordance with the amount of steam or air blast present, there may be predetermined the amount or rate of fuel-feed for the number of cubic feet of gas desired to be produced. The successful experiment has been made of burning from 250 to 1,500 pounds of coal per hour, using 2.5 up to 30 lbs. steam pressure, in the same producer, to determine whether the latter will satisfy, merely by changing the pressure and rate of rotation, any given consumption of coal and production of gas. In this embodiment of the invention, it will be noted that the stirring and poking effect may be confined to its proper zone (that surrounded by the section 9) and the ash-discharging effects confined also to its proper zone (that surrounded by the section 10.) It will be seen, too, that here the stirring members 44 are effective for breaking up and leveling the coal, after the same has passed from the interior of partition 30; thereby preventing porosity in the fire-bed, aiding to shake down the ashes, and comprising an adequate and less costly and worrisome substitute for the old hand poking or the heretofore utilized mechanical pokings. The poker 45 (or 45') is illustratively disclosed, however, and the same, or a substitute therefor, may be used, preferably to bear against the inner wall of the section 9 to prevent the for-

mation of clinkers so sure to occur to some extent in any producer.

Referring now particularly to the presently disclosed possible constructions of partition 30 (hereinafter referred to as "hopper 30"), attention is directed first to Figs. 1, 2 and 3. Fig. 2 shows (as does also Fig. 7) a preferable method of building up section 10, (and, if desired, the other sections 10 employed), that is, by assembling as shown, and preferably suitably bonding together, the arcuate sub-divisions 51; this construction resulting in an important economy and convenience of construction. The hopper 30 may, if desired, be braced in position by a suitable plurality of the struts 52 (not shown in Fig. 2), or by a suitable plurality of the hollow pipes 53 (which are preferably hollowed for a water-cooling circulation 20 therethrough as hereinafter described, inasmuch as the location of said pipes is adjacent the combustion zone), or otherwise. To guide the rockable poker 45 or 45', if employed, two of the pipes 53 are preferably parallelly associated as shown in Figs. 2 and 7,—a description of the parts shown in the latter figure being below set forth.

The hopper 30 may be made of a single casting, hollowed to establish, or otherwise carrying, conduits for a cooling circulation or circulations as desired, or it may be built up of a plurality of assembled sub-divisions 54 as shown in Figs. 2 and 7.

Various possible cooling circulations are shown in Figs. 2 and 3. As shown best in Fig. 2, the circulation 55—55 may traverse the interiors of sub-divisions 51, the pipes 53, the sub-divisions 54, and the connecting tubes 56; the circulation 57—57 may traverse one half of the lower periphery of the hopper 30 and the ribs 59; and the circulation 58—58 may traverse the other half of the said periphery and said ribs 59. It is seen that at the points 54' in Fig. 2, certain of these circulations apparently blend; but in Fig. 3 a suitable method of construction of the hopper 30 is shown at 55 and 58 (compare Fig. 1 at 55). These circulations, or any two of them, may, if desired, have a common inlet conduit and a common outlet conduit, the latter, as indicated at 60, 61 and 62, in Fig. 1, preferably uniting with the water seals 47 and 28 and eventually letting into the collected liquid in basin 20. And still another possible cooling circulation, in this instance a continuous one, is disclosed at 63—63 in Figs. 1 and 7, the hopper 30 not being here disclosed as carrying the ribs 59 (Fig. 2) and the circulation traversing the interiors of sub-divisions 51, the pipes 53, sections of the lower peripheral edge of hopper 30 and the connecting tubes 56. This circulation, too, may have its outlet conduit suitably let into the basin 20.

The circulation just described, preferably

confined as it is with reference to the hopper to the latter's lower peripheral edge, is believed to be practicable, inasmuch as said edge only is in close proximity to the combustion zone.

If the hopper 30 were made with double concentric side walls in place of the ribs 59 (as indicated at 64 in Fig. 1), it would be within the province of this invention, but this would probably cause a too extreme 75 cooling effect, which would act to chill the outgoing gases.

Particular attention is directed to the plurality of spaced studs 65 or the like shown in Fig. 1, which could with particular advantage be used in connection with the hopper and cooling circulation shown in Fig. 7, and the function of which will now be described.

It has been aimed to secure the benefits of 85 hanging the hopper 30 in such a way as to provide a steady feeding of fuel for partially gasifying the coal, and as to provide a carrying over of the generated heavy hydrocarbon gases directly into the annular 90 space between the hopper and section 8, to the end that these heavy gases may combine with the lighter CO gases to become more fixed and cooled down to about half the initial heat of the CO, CO₂, and H gases 95 evolved from the hot-fired zone. This sends forth the final gases cooled and fixed, and nearly free from the suspended tar and soot. There is believed to be no actual combustion of coal until the same falls below the hopper. There is a very considerable distillation 100 of heavy hydrocarbon, with much coking action. Now in order to keep the hopper from cutting or wearing away or being distorted by heat, it would be desirable to coat 105 the entire outside surface of the hopper with a layer of gas-carbon (solidified coke and tar). This is an excellent heat insulator and normally gradually forms about and upon the hopper, and is burned thereon and held 110 in place by its entanglement with the studs 65. A coating is thus economically and automatically adopted by the hopper, which 115 will preclude any chilling effect upon the gases being produced.

It will thus be seen that I have provided a producer of great efficiency, simplicity and economy.

Inasmuch as many changes could be made in the above construction, and many apparently widely different embodiments of my invention could be made without departing from the scope thereof, it is intended that all matter contained in the above description or shown in the accompanying drawings 120 shall be interpreted as illustrative and not in a limiting sense.

It is also to be understood that the language used in the following claims is intended to cover all the generic and specific 130

features of the invention herein described and all statements of the scope of the invention which, as a matter of language, might be said to fall therebetween.

Having described this invention, what I claim as new, and desire to secure by Letters Patent, is:

1. A gas producer, having two sections, both of which are rotatable, means for driving one of the sections, and means for coupling the two sections together at will.

2. A gas producer, having two sections, both of which are rotatable, means for driving one of the sections, means for coupling the two sections together at will, one of the sections inclosing the combustion zone and the other the ash zone.

3. A gas producer, having two sections, both of which are rotatable, means for driv-

ing one of the sections, means for coupling the two sections together at will, one of the sections inclosing the combustion zone and the other the ash zone, and a twyer-box extending into the ash zone.

4. A gas producer, having two sections, both of which are rotatable, means for driving one of the sections, means for coupling the two sections together at will, one of the sections inclosing the combustion zone and the other the ash zone, and a non-circular twyer-box extending into the ash zone.

In witness whereof, I have hereunto signed my name in the presence of two witnesses.

JAMES A. HERRICK.

In the presence of—

FRANK J. KENT,
ALDA L. MILLER.
